UNITED STATES PATENT OFFICE

MARCIANO CALDERON, OF LONDON, ENGLAND

HAIR WAVING APPARATUS

Application filed November 18, 1930, Serial No. 496,505, and in Great Britain November 18, 1929.

This invention relates to improvements in hair waving apparatus, and has for its chief object to provide an efficient and neat hair waving device.

5 The system of hair waving for which the present form of apparatus is intended is that in which steam is brought into contact with the hair and, according to this invention, the device comprises a self-contained steam generator, in close contact with the head of the subject, which is provided with a tube or the like to receive the curler on which a tress of hair is wound, means being provided to conduct the steam from the generator to the 10 tube or the like.

In order that this invention may be the more clearly understood and readily carried into effect, I will proceed to describe the same with reference to the accompanying drawings which illustrate by way of example and 20 not of limitation one convenient form of this invention, and in which

Figure 1 is a view of a device according to this invention in use, and

25 Figure 2 is a view showing the device when not in use.

Figure 3 is a central vertical section through the device, and

30 Figures 4 and 5 show the parts of the steam generator.

Referring to the drawings, the device, which may have an overall length of, say, six inches so as to be of the same length as the usual type of these devices, comprises a tube 35 *a* surrounded by a further tube *b* which is arranged to leave an annular space *c* around the tube *a*. The tube *b* tapers towards the free end of the tube *a* (hereinafter called the "scalp end" of the device as it is this end which, when the device is in use, lies close to the scalp) so that the annular space *c* is of gradually decreasing cross section towards the scalp end of the device. The scalp end 40 of the tube *b* is provided with a collar *b*¹.

45 These tubes may be caused to slide into similar extension tubes to fit at the scalp.

The upper ends of the tube *a* and *b* are kept in position by means of an annular plug or 50 ring *d* which plug fits friction-tight into

the tube *b* and into which the upper end of the tube *a* is screwed.

The assembly of the two tubes *a* and *b* is carried by a plate *e* having a central boss *e*¹ to take into the internal bore of the tube *a* and also having an upstanding annular projection *e*² over which takes a tube *f* to form a chamber *f*¹ above the plate *e*. Secured in position in the centre of the plate *e* is a tube *g*, the lower end of which passes through the boss *e*¹, as shown in Figure 3, to communicate with the tube *a*, and the upper end of which extends above the upper edge of the tube *f*. Carried by this tube *g* so as to form a single unit with the same and with the plate *e* (see Figure 5) is a chamber *g*¹ surrounding the tube *g* and provided with two tubes, one *g*² passing through the plate *e* in such a position as to communicate with the annular space *c* between the tubes *a* and *b*, and the other *g*³, being turned through a semi-circle and being extended upwards so as to lie within the chamber *f*¹ and to terminate above the level of the upper end, thereof, the upper end being provided, below the level of the upper edge of the tube *f*, with a hole *g*⁴, the purpose of which will be herein-after described.

Surrounding the chamber *g*¹ is a double walled tubular member *h*, the annular space *h*¹ between the walls of which is adapted to receive an electric heating element *h*² wound on a former *h*³ and carried by a carrier *h*⁴ having a plug *h*⁵ to close the upper end of the bore of the tube *h* and also to close the upper end of the annular space *h*¹. This carrier *h*⁴ is preferably made of insulating material and serves to enable the connection between the electric flexible connection *j* and the heating element *h*² to be made. The major portion of the carrier *h*⁴ projects above the level of the upper edge of the tube *f*.

The upper end of the tube *f* is closed by a cover plate *k* held in position by means of the pillars *k*¹ on the plate *k*. The plate *k* fits on to the tube *f* in such a manner as to make the chamber *f*¹ substantially air tight. The cover *k* is provided with a hole through which the upper end of the tube *g*³ passes and is also

provided with a spring-controlled safety valve, indicated at k^2 .

5 Fitting into the top of the tube g^3 is a further tube l having a hole l^1 which can be brought into register with the hole g^4 in the tube g^3 by operation of the handle l^2 secured to the closed upper end of the tube l .

10 Describing now the operation of the device, the chamber f^1 , which has previously been filled with cotton wool or like absorbent material (not shown) is filled with water or hair waving solution and the current for the heating element is switched on. The liquid is raised to its boiling point and the steam or other vapour rising to the top of the chamber f^1 is admitted to the tube g^3 by reason of the holes g^4 and l^1 being in register, and passing along this tube reaches the chamber g^1 . Here again the steam or other vapour is subjected to the heating action of the heating element h^1 and consequently by the time it emerges through the tube g^2 it is superheated. Previous to the switching on of the current, a rubber tube m is passed over the end of the 15 outer tube b and this rubber tube is tied, as at m^1 , to the roots of the hair n on the curler (not shown) which has been inserted into the inner tube a . The steam or the like passes down the annular space c and is thus led to the roots of the hair and percolates through the whole length of the hair before passing out of the central tube g communicating with the upper end of the tube a , as above described. The hair treated in this way is 20 thus submitted to a continuous and strong discharge of superheated steam or the like and since the steam is caused to pass through the centre of the heating unit on its exit, it is prevented from condensing.

25 40 It will thus be seen that the heating unit according to this invention is self-contained, neat and efficient.

Many modifications may be made in the above described form without departing 45 from the spirit of this invention, for example, the device may be in two parts if desired, comprising the heater portion and the tube portion, or the tube portion to receive the curler may be in two parts. Again, instead 50 of conducting the steam to the scalp end of the device by means of the annular space, one or more small tubes may be arranged down the side of the tube for the curler to conduct the steam or the like to the scalp 55 end of the device. Further, if desired, the steam may be caused to pass down the device towards the scalp end of the same instead of passing up the tube from the scalp end.

I claim:—

60 1. Self contained hair waving apparatus comprising a chamber to receive liquid, the vapour of which is used to treat the hair, an electrical heating element adjacent said chamber to convert said liquid into vapour, a 65 space adjacent said electrical heating ele-

ment, a tube to receive a curler on which the hair to be treated is wound, means for conducting the vapour from said space to said tube and means for conducting the vapour generated in said chamber through said space before passing to the tube, whereby the vapour is superheated before coming in contact with the hair.

2. Self contained hair waving apparatus, according to claim 1, in which a tube communicates between said space and the scalp end of the curler receiving tube, whereby the superheated vapour is caused to pass through the whole tress of hair before leaving the apparatus.

3. Self contained hair waving apparatus comprising a chamber to receive liquid, the vapour of which is used to treat the hair, an electrical heating element adjacent said chamber to convert said liquid into vapour, a space adjacent said electrical heating element, a tube to receive a curler on which the hair to be treated is wound, means conducting the vapour from said chamber into said space in order to superheat the same, means connecting said space to the scalp end of the tube in order that the vapour shall pass through the whole tress of hair before leaving the apparatus, said vapour also passing in its passage out of the apparatus close to 90 said electrical heating element in order again to heat the vapour and prevent condensation.

4. Self contained hair waving apparatus comprising a chamber to receive liquid, the vapour of which is used to treat the hair, a removable electrical heating element adjacent said chamber to convert said liquid into vapour, a space adjacent said electrical heating element, a tube to receive a curler on which the hair to be treated is wound, means for conducting the vapour from said space to said tube and means for conducting the vapour generated in said chamber through said space before passing to the tube, whereby the vapour is superheated before coming in contact 100 with the hair.

5. Self contained hair waving apparatus comprising a chamber to receive liquid, the vapour of which is used to treat the hair, a removable electrical heating element adjacent 110 said chamber to convert said liquid into vapour, a space adjacent said electrical heating element, a tube to receive a curler on which the hair to be treated is wound, means conducting the vapour from said chamber into said space in order to superheat the same, means connecting said space to the scalp end of the tube in order that the vapour shall pass through the whole tress of hair before 120 leaving the apparatus, said vapour also passing in its passage out of the apparatus close to said electrical heating element in order again to heat the vapour and prevent condensation.

6. Self contained hair waving apparatus 130

comprising an annular chamber to receive liquid, the vapour of which is used to treat the hair, an electrical heating element surrounded by said chamber to convert said liquid into vapour, a space adjacent said electrical heating element, a tube to receive a curler on which the hair to be treated is wound, means for conducting the vapour from said space to said tube and means for conducting the vapour generated in said chamber through said space before passing to the tube, whereby the vapour is superheated before coming in contact with the hair.

7. Self contained hair waving apparatus, comprising an annular chamber to receive liquid, the vapour of which is used to treat the hair, an annular electrical heating element surrounded by said chamber to convert said liquid into vapour, the space surrounded by said annular electrical heating element, a tube to receive a curler on which the hair to be treated is wound, means conducting the vapour from said chamber into said space in order to superheat the same, means connecting said space to the scalp end of the tube in order that the vapour shall pass through the whole tress of hair before leaving the apparatus, said vapour also passing in its passage out of the apparatus close to said electrical heating element in order again to heat the vapour and prevent condensation.

8. Self contained hair waving apparatus comprising a chamber to receive liquid, the vapour of which is used to treat the hair, an electrical heating element adjacent said chamber to convert said liquid into vapour, a space adjacent said electrical heating element, a tube to receive a curler on which the hair to be treated is wound, means for conducting the vapour from said space to said tube, means for conducting the vapour generated in said chamber to said space in order to superheat the same and means for controlling the supply of vapour from said chamber to said space.

9. Self contained hair waving apparatus comprising a chamber to receive liquid, the vapour of which is used to treat the hair, an electrical heating element adjacent said chamber to convert said liquid into vapour, a space adjacent said electrical heating element, a tube to receive a curler on which the hair to be treated is wound, means for conducting the vapour from said chamber into said space in order to superheat the same, means for controlling the supply of vapour from said chamber to said space, means connecting said space to the scalp end of the tube in order that the vapour shall pass through the whole tress of hair before leaving the apparatus, said vapour also passing in its passage out of the apparatus close to said electrical heating element in order again to heat the vapour and prevent condensation.

10. Self contained hair waving apparatus

comprising an annular chamber to receive liquid, the vapour of which is used to treat the hair, an annular electrical heating element surrounded by said chamber in order to convert said liquid into vapour, a space ⁷⁰ surrounded by said annular electrical heating element, a tube to receive a curler on which the hair to be treated is wound, means for conducting the vapour from said chamber into said space in order to superheat the ⁷⁵ same, means for controlling the supply of vapour from said chamber to said space, means connecting said space to the scalp end of the tube in order that the vapour shall pass through the whole tress of hair before ⁸⁰ leaving the apparatus, said vapour also passing in its passage out of the apparatus close to said electrical heating element in order again to heat the vapour and prevent condensation.

11. Self contained hair waving apparatus comprising a chamber to receive liquid, the vapour of which is used to treat the hair, a safety valve to said chamber, an electrical heating element adjacent said chamber, to ⁹⁰ convert said liquid into vapour, a space adjacent said electrical heating element, a tube to receive a curler on which the hair to be treated is wound, means for conducting the vapour from said space to said tube and means for conducting the vapour generated in said chamber through said space before passing to the tube, whereby the vapour is superheated before coming in contact with the hair.

12. Self contained hair waving apparatus comprising a chamber to receive liquid, the vapour of which is used to treat the hair, a safety valve to said chamber, an electrical heating element adjacent said chamber to convert said liquid into vapour, a space adjacent said electrical heating element, a tube to receive a curler on which the hair to be treated is wound, means conducting the vapour from said chamber into said space in order to superheat the same, means connecting said space to the scalp end of the tube in order that the vapour shall pass through the whole tress of hair before leaving the apparatus, said vapour also passing in its passage out of the apparatus close to said electrical heating element in order again to heat the vapour and prevent condensation.

13. Self contained hair waving apparatus comprising an annular chamber to receive liquid, the vapour of which is used to treat the hair, a safety valve to said chamber, an annular electrical heating element surrounded by said chamber to convert said liquid into vapour, a space surrounded by said annular electrical heating element, a tube to receive a curler on which the hair to be treated is wound, means conducting the vapour from said chamber into said space in order to superheat the same, means connecting said space ¹²⁰

¹²⁵

¹³⁰

to the scalp end of the tube in order that the vapour shall pass through the whole tress of hair before leaving the apparatus, said vapour also passing in its passage out of the apparatus close to said electrical heating element in order again to heat the vapour and prevent condensation.

14. Self contained hair waving apparatus comprising a chamber to receive liquid, the vapour of which is used to treat the hair, a safety valve to said chamber, an electrical heating element adjacent said chamber to convert said liquid into vapour, a space adjacent said electrical heating element, a tube to receive a curler on which the hair to be treated is wound, means for conducting the vapour from said space to said tube, means for conducting the vapour generated in said chamber to said space in order to superheat the same and means for controlling the supply of vapour from said chamber to said space.

15. Self contained hair waving apparatus, comprising an annular chamber to receive liquid, the vapour of which is used to treat the hair, a safety valve to said chamber, an annular electrical heating element surrounded by said chamber in order to convert said liquid into vapour, a space surrounded by said annular electrical heating element, a tube to receive a curler on which the hair to be treated is wound, means for conducting the vapour from said chamber into said space in order to superheat the same, means for controlling the supply of vapour from said chamber to said space, means connecting said space to the scalp end of the tube in order that the vapour shall pass through the whole tress of hair before leaving the apparatus, said vapour also passing in its passage out of the apparatus close to said electrical heating element in order again to heat the vapour and prevent condensation.

In testimony whereof I have signed my name to this specification.

MARCIANO CALDERON.
